(57) **CLAIM**

The ornamental design for a watchband for smart watch, as shown and described.

DESCRIPTION

FIG. 1 is a perspective view of a watchband for smart watch showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are for the purpose of illustrating portions of the watchband for smart watch that form no part of the claimed design.

1 Claim, 8 Drawing Sheets(56)
